(57) **CLAIM**

The ornamental design for a tire, as shown and described.

DESCRIPTION

FIG. 1 is a front right perspective view of a first embodiment of a tire showing our new design, the opposite side perspective being identical thereto, it being understood that the dashed lines form no part of the claimed design;

FIG. 2 is a front elevation view thereof, it being understood that the dashed lines form no part of the claimed design;

FIG. 3 is a left elevation view thereof, it being understood that the dashed lines form no part of the claimed design;

FIG. 4 is a right elevation view thereof, it being understood that the dashed lines form no part of the claimed design;

FIG. 5 is a sectional view taken along section line 5-5 of the tire shown in FIG. 2, it being understood that the dashed lines form no part of the claimed design;

FIG. 6 is a front right perspective view of a second embodiment of a tire showing our new design, the opposite side perspective being identical thereto;

FIG. 7 is a front elevation view thereof;

FIG. 8 is a left elevation view thereof;

FIG. 9 is a right elevation view thereof; and,

FIG. 10 is a sectional view taken along section line 10-10 of the tire shown in FIG. 7.
